UNITED STATES PATENT OFFICE.

WLADIMIR KAVAN, OF NEW YORK, N. Y.

DESIGN FOR A BARBER'S POLE.

57,978.

Specification for Design.

Patented May 24, 1921.

Application filed September 4, 1920. Serial No. 408,370. Term of patent 3½ years.

To all whom it may concern:

Be it known that I, WLADIMIR KAVAN, a citizen of Moravia, Europe, residing in New York city, in the county of New York and State of New York, have invented a new, original, and ornamental Design for a Barber's Pole, of which the following is a specification, reference being had to the accompanying drawing, forming part thereof.

The figure is an elevation of a barber's pole, showing my new design.

I claim:

The ornamental design for a barber's pole, as shown.

WLADIMIR KAVAN.
